BOX LINER

James Monroe Smith, Shelbyville, Ind., assignor
to The Kennedy Car Liner & Bag Co., Shelby-
ville, Ind., a corporation of Indiana

Application January 2, 1934, Serial No. 705,006

1 Claim. (Cl. 217—3)

The invention forming the subject matter of this application is a paper liner adapted to be formed into the shape of the interior of a packing box or the like, for the purpose of ensuring a proper sealing of material adapted to be packed in the box.

The main object of the invention is to provide a liner of the character described which can be formed from a blank materially less in area than liners heretofore used for the same purpose.

Another object of the invention is to provide a liner of the character described which can be readily assembled for quick installation in packing boxes and the like.

Another object of the invention is to provide a liner of this type having triangular portions adapted to extend above the top of the packing box during the filling of the same, and to be folded over the contents of the box to form a complete seal for such contents.

A further object of the invention is to provide a box liner in which the parts extending above the top edges of the box can be folded back during the packing operation to permit more convenient filling of the lined box.

Other objects of the invention will become apparent as the detailed description thereof proceeds.

In the drawing:

Figure 1 is a plan of a blank from which the liner is constructed;

Figure 2 is a perspective view of a liner having the parts thereof folded up and assembled in the relative positions required for proper lining of the box;

Figure 3 is a perspective view of a box having a liner arranged therein in position to seal the contents of the box, part of the box being broken away to show the assembled and sealed liner;

Figure 4 is a plan view of the box liner with the parts arranged as shown in Figure 2 of the drawing.

The liner, as shown in the drawing, is adapted to be cut from a continuous roll of paper, with practically no waste involved in the folding and assembling thereof into finished form. The liner as shown in Figure 1 is designed for use in a square packing box. The blank 1 from which it is formed, is, therefore, square when developed, as shown in Figure 1. The dimensions of the blank depend upon the area of the bottom of the box and the depth of the sides thereof. For example, the bottom of the liner between the creases 2 and 3, is equal to the distance between

the one pair of opposite sides of the box. Similarly, the distance between the creases 4 and 5 of the liner is equal to the distance between the other pair of opposite sides of the box.

The creases 2 and 3 are drawn parallel to the diagonal 6 of the blank; and the creases 4 and 5 are drawn parallel to the diagonal 7 of the same blank. These pairs of creases are symmetrically arranged on the opposite side of the said diagonals 6 and 7; and are continued in opposite direction from the diagonals through a distance a equal to the depth of the box into which the liner is to be inserted. The outer edges of the blank extend at an angle of 45° to the diagonals 6 and 7 and pass through the prolongations of the creases 2, 3, 4, and 5 at the distance a from each of said creases.

To provide for a folding of the liner into finished form, the parts of creases 2 and 3 extending in opposite direction from the creases 4 and 5 are cut to provide slits 8, 9, 10, and 11. In the assembling of the liner into finished form, the blank is folded up about the creases 2 and 3 to form the rectangular sides 12 and 13, having triangular portions 14 and 15 extending upwardly therefrom. The blank is likewise folded about the creases 4 and 5 to form the rectangular sides 16 and 17 having the triangular portions 18 and 19 extending from their upper edges. The triangular flaps 20 and 21 are folded against the sides 16 and 17 and are pasted thereto. Similarly, the triangular flaps 22 and 23 are folded against the sides 16 and 17 and are pasted thereto. In this condition, the liner assumes the position illustrated in Figures 2 and 4 of the drawing.

It is obvious from inspection of Figures 2 and 3 that the liner, when assembled, will maintain its sides and the triangular flaps extending therefrom in substantially vertical positions; so that the liner may be readily inserted into a box. After the lined box is filled with material, the triangular flaps 14, 15, 18, and 19, may be folded over the top of the material to seal the same completely.

The completed liner assembled in a packed box is shown in Figure 3 of the drawing. In this figure the box is shown as comprising a bottom 24, sides 25 and 26 and a top 27. The relative position of the several parts of the liner are clearly indicated in Figure 3, as will be apparent from the reference numerals applied to said parts in the said Figure 3.

While I have described the liner as adapted for use with a box which is square in horizontal cross section, it must be understood that the in-

vention is not limited to such use, since the blank may be laid out in substantially the same manner to adapt it for use in boxes of different dimensions in directions at right angles to each other.

5 What I claim is:

A box liner comprising a rectangular sheet of material folded to form a rectangular lining for the bottom and sides of a box, triangular flaps 10 extending above the top edges of said sides, said

top edges forming the bases of said triangles said flaps being adapted when folded inwardly to cover the same area as the bottom or top of the box, said sheet being cut to provide triangular flaps on the opposite ends of one pair of opposite sides adapted to be folded against and secured to the opposite ends of the outer faces of the other pair of sides to form an assembled liner for said box.
